(57) **CLAIM**

The ornamental design for a carpenters square, as shown and described.

DESCRIPTION

FIG. 1 is a rear perspective view of a carpenters square, showing my new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

The dash-dot-dash lines define the bounds of the claimed design, while all other broken lines illustrate environmental subject matter and form no part of the claimed design.

1 Claim, 4 Drawing Sheets
